UNITED STATES PATENT OFFICE.

FELIX EBERHART, OF NEWARK, NEW JERSEY, ASSIGNOR TO AMERICAN CAN COMPANY, OF NEW YORK, N. Y., A CORPORATION OF NEW JERSEY.

LAP-SEAM CAN.

1,227,596.

Specification of Letters Patent.

Patented May 29, 1917.

Application filed April 17, 1915. Serial No. 21,978.

To all whom it may concern:

Be it known that I, FELIX EBERHART, a citizen of the United States, residing in Newark, in the county of Essex and State 5 of New Jersey, have invented a new and useful Improvement in Lap-Seam Cans, of which the following is a specification.

My invention relates in general to lap seam metal cans and has for its object 10 broadly the elimination or hiding of the raw edge within the can which is usually provided in such construction.

An important object of the invention is the provision of a lap seam can formed of 15 previously coated material, so constructed that no uncoated edge or surface is present within the can.

In the packaging of shrimp and other similar products it is the custom to provide 20 the can body with an internal coating so that the contents cannot corrode the metal. This coating is usually and preferably applied to the sheet from which the can blanks are cut. Prior to my invention consider- 25 able difficulty has been experienced because of the failure, where the material of the can has been coated before the can is constructed, to provide means for preventing corrosion of the raw edge formed in cutting the can blank which forms the inner of 30 the two over-lapping edges in the lap seam. If this edge, narrow as it is, be left unprotected a black streak is produced on the contents of the can. This evil my invention 35 aims to eliminate, through the provision of a lap-seam can of previously coated material which presents no uncoated metal within the can.

Other objects and advantages of the invention will be apparent as it is better understood from the following description when considered in connection with the accompanying drawing illustrating a preferred embodiment thereof.

On the drawing,

Figure 1 is a horizontal section taken through a can embodying my invention;

Fig. 2 is a vertical section through the same;

Fig. 3 is an enlarged detail section across the seam;

Fig. 4 is a partial sectional view of the seam with the cover in place; and

Fig. 5 is a similar view showing the top or bottom of the can before flanging.

For the purpose of illustrating my invention, I have shown it embodied in a cylindrical can 4 of the lap seam type. In this form of can the two side edges 5 and 6 of the sheet forming the body are merely over- 60 lapped and soldered together. In accordance with a more or less common custom of coating these sheets before the body is formed and even before the blanks are cut, the can shown on the drawing is provided 65 with an internal coating 7 of enamel or other protective material. The inner edge 6 of the side seam is cut out at its ends and is bent outwardly and back upon itself at 8 and the bent back portion 9 thus provided 70 is disposed against the coated face of the outer overlapping edge 5. When thus bent the protective coating extends around so much of the edge 6 as is exposed within the can. This not only forms a continuous 75 coating about the inside of the can but also eliminates the raw edge therefrom which, in addition to possessing the disadvantages already set forth, provide a jagged or sharp edge in the can. As the ends of the edge 80 are cut away the folding back or bending of the edge does not interfere with the construction of the connection between the cover and body. When the solder is applied the enamel of the two parts fuses together 85 and the coating is thus made continuous.

It is thought that the invention and many of its attendant advantages will be understood from the foregoing description, and it will be apparent that various changes 90 may be made in the form, construction and arrangement of the parts without departing from the spirit and scope of the invention or sacrificing any of its material advantages, the form hereinbefore described 95 being merely a preferred embodiment thereof.

I claim:

1. A container comprising a body formed of a sheet of suitable material secured along 100 its edges in a lap seam and provided with a protective coating on its inner face, the

inner edge of the sheet in said seam being bent back upon itself and in contact with the outer edge of said seam, and the outer edge of the sheet being applied flat on the outer surface of the container beyond said bent-back edge.

2. A container comprising a body formed of a sheet provided with a protective coating on the side of the sheet forming the internal surface of said container, the edges of said sheet being secured together in a lap seam, the inner of said edges being bent back upon itself and closed within the seam, and the outer edge of the sheet being applied flat on the outer surface of the container beyond said bent-back edge.

3. A container comprising a sheet of metal secured along its edges in a lap seam, the inner of said edges being folded back

upon itself against the portion of the sheet 20 adjacent the outer of said edges, and the outer edge of the sheet being applied flat on the outer surface of the container beyond said bent-back edge.

4. A container of the lap seam type and 25 of material provided with a protective coating applied previously to the formation of the container, the inner of the lapped portions having an outwardly doubled edge and said coating being continuous within 30 the finished can.

Signed in the presence of two subscribing witnesses.

FELIX EBERHART.
